UNITED STATES PATENT OFFICE

149,609

DESIGN FOR A PIN

Roy G. Biggins, Kansas City, Kans.

Application December 11, 1946, Serial No. 135,403

Term of patent 14 years

(Cl. D45—19)

To all whom it may concern:

Be it known that I, Roy G. Biggins, a citizen of the United States, residing at Kansas City, in the county of Wyandotte and State of Kansas, have invented a new, original, and ornamental Design for Pins, of which the following is a specification, reference being had to the accompanying drawing, forming part thereof.

Fig. 1 is a top view of the pin, showing my new design.

Fig. 2 is a front elevation of the pin.

Fig. 3 is an end elevation of the pin.

I claim:

The ornamental design for a pin, as shown.

ROY G. BIGGINS.
